UNITED STATES PATENT OFFICE

WILLIAM W. ZINNAMON, OF TULSA, OKLAHOMA

CARBURETOR

Application filed December 1, 1932. Serial No. 645,151.

This invention relates to certain new and useful improvements in carburetors.

The primary object of the invention is to provide a carburetor especially designed for the use of natural gas and embodies valve mechanism operative at slow starting speed for the passage therethrough to the throttle valve of an excess quantity of gas with respect to air fed to the carburetor to facilitate starting of an internal combustion engine with the subsequent operation of a main valve accomplished automatically in the presence of increased suction in the intake manifold with a regular bow tensioned air valve to insure proper proportions of gas and air through the engine.

With the above and other objects in view that will become apparent as the nature of the invention is better understood, the same consists in the novel form, combination and arrangement of parts hereinafter more fully described, shown in the accompanying drawing and claimed.

In the drawing:—

Figure 1 is a side elevational view of a carburetor constructed in accordance with the present invention and especially designed for the use of natural gas;

Figure 2 is a vertical longitudinal sectional view of the carburetor showing the non-seating tensioned air inlet valve with the main floating gas control valve and auxiliary valve carried by the main valve;

Figure 3 is a cross-sectional view taken on line 3—3 of Figure 2 showing the radial partitions in the mixing chamber of the carburetor; and

Figure 4 is a perspective view of the main gas valve in the carburetor.

Referring more in detail to the accompanying drawing, there is illustrated a carburetor designated in general by the reference character 10 and including a body portion 11 carrying a head 12, the body 11 having a lateral tube connection 13 with an air chamber 14.

The body 11 in the form of a chamber as shown in Figure 2 is provided with a bottom wall 15 having a central opening therein forming the valve seat 16 and a depending

internally threaded nipple 17 to facilitate attachment of the carburetor body with a natural gas supply pipe or other conduit. The upper end of the body 11 is ground to provide a valve seat 18, the head 12 having a base flange 19 clamped upon the upper end of the body in surrounding relation to the valve seat 18. The head 12 has an upstanding reduced neck portion 20 with a main gas throttle valve 21 pivoted therein and operated by the exteriorly positioned lever 22, the upper end of the neck 20 carrying an apertured flange 23 to facilitate attachment of the carburetor to the intake manifold of an internal combustion engine. In actual practice this carburetor has especially demonstrated high efficiency when employed upon four, six and eight cylinder high-speed internal combustion engines.

The valve mechanism confined within the body 11 and head 12 includes a tubular valve stem 24 having a conical valve 25 upon its lower end cooperating with the valve seat 16 of the carburetor body, inclined ports 26 in the conical valve 25 forming communication between the gas supply pipe or conduit and the bore 24a in the tubular valve stem 24. When the conical valve 25 is engaged with its seat 16, the upper end of the tubular valve stem 24 terminates above the valve seat 18, the upper end of the tubular valve stem 24 being externally threaded to receive the threaded central bushing 27 of the main disk valve 28 that is retained in position on the valve stem by the jamb nut 29.

The auxiliary valve includes a disk 30 mounted upon the upper side of the main disk valve 28 and is mounted theron for limited movement by means of the headed pins 31 extending through openings in the peripheral edge of the valve 30 and anchored in the main valve 28, the auxiliary disk valve 30 cooperating with the valve openings 32 arranged in circular series in the main valve 28.

The valve mechanism including the tubular stem 24, main and auxiliary valves and conical valve 25 is loosely mounted in the carburetor, being guided at its lower end by the pin 33 depending from the conical valve 25 and extending into the nipple 17 while the

upper end of the valve mechanism is guided in its movement by the radial ribs 34 extending inwardly from the side walls of the head 12 as shown in Figures 2 and 3. Four of these ribs 34 are preferably provided and divide the lower end of the head 12 into four mixing chambers for air and gas entering the head by way of the valve mechanism.

As shown in Figure 2, the tube 13 forms 10 unobstructed communication between the air chamber 14 and the body portion 11 of the carburetor, the valve mechanism in the air chamber 14 for controlling the admission of air therein through the body opening 35 comprising a valve stem 36 carrying a disk valve 37 at its lower end and extending upwardly through the top wall 38 of the air chamber and adjustable threaded bushing 39 to receive a nut 40 upon its upper terminal end 15 adjustably threaded thereon with a coil spring 41 interposed between the nut and upper end of the bushing 39. The lower end of the valve stem within the air chamber 14 is surrounded by a coil spring 42 engaging 20 at its lower end, the disk 43 seated on the valve plate 37 and engaged at its upper end with the disk plate 44 surrounding the valve stem 36 and engaged with the lower end of the bushing 39. The valve 37 is non-seating 25 with respect to the air opening 35 in the lower end of the air chamber 14, the two springs 42 and 41 being variably tensioned by means of the adjusting nut 40 to regulate the amount of air to pass through the opening 35 into the 30 air chamber and automatically operating to permit further movement of the valve 37 away from the air opening 35 in the presence of increased suction conditions in the intake manifold of an internal combustion engine 35 for the proper admixture of air and gas flowing through the carburetor.

When the internal combustion engine is at rest, the conical valve 25 is engaged with the valve seat 16, the disk valve 28 engaged with 40 the valve seat 18 while the auxiliary disk valve 30 closes the valve openings 32 in the disk valve 28. To start the engine at slow speed, the suction initially created in the intake manifold of the engine unseats the auxiliary valve 30 to uncover the openings 32 in the main valve disk 28, gas flowing through the inclined ports 26 and bore 24a in the tubular valve stem 24 and through the reduced openings in the upper end of the bore 24a 45 to be directed laterally by the auxiliary disk valve 30 while air from the chamber 14 flowing therethrough by way of the bottom opening 35 passes through the openings 32 in the main valve disk 28 for admixture with the gas. When suction in the intake manifold 50 of the gas engine increases, the main disk valve 28 is unseated or raised from the valve seat 18, the gas then flowing by way of the valve opening 16 to be directed laterally by 55 the main disk valve 28, the auxiliary valve

30 then gravitationally closing upon the main valve, the intake of air travelling in the same direction by way of the valve 28 and into the mixing chamber above the main valve. Increased suction in the engine operates to move the disk valve 37 of the air control away from the opening 35 to increase the area thereof for the proper admixture of gas and air. The initial feeding of the gas by the unseating of the auxiliary valve 30 prevents the flooding of the engine with gas and thereby restricts the gas feed to the engine at slow starting speed.

From the above detailed description of the invention, it is believed that the construction and operation thereof will at once be apparent and while there is herein shown and described the preferred embodiment of the invention, it is nevertheless to be understood that minor changes may be made therein without departing from the spirit and scope 80 of the invention as claimed.

I claim:—

1. In a natural gas carburetor, a body, an air inlet chamber, a conduit connecting the body and air chamber, a non-seating variably tensioned valve in the air chamber, floating valve mechanism in the body to control the flow of air and gas therethrough, including a tubular valve stem, a main valve, a valve on the stem, controlling flow of gas to the main valve and an auxiliary valve on the main valve, means forming unobstructed communication between the gas supply and bore of the tubular valve stem and said main valve having air passage openings therein normally closed by the auxiliary valve.

2. In a natural gas carburetor, a body, an air inlet chamber, a conduit connecting the body and air chamber, a non-seating variably tensioned valve in the air chamber, and floating valve mechanism in the body to control the flow of air and gas therethrough, including a tubular valve stem having a valve at its lower end engageable with a seat for controlling flow of gas into the body, a main valve on the upper end of the stem engageable with a seat in the body, the valve at the lower end of the stem being constructed for admitting gas to the bore of the tubular valve stem and auxiliary valve carried by the main valve for closing the bore at the upper end of the tubular valve stem.

3. In a natural gas carburetor, a body, an air inlet chamber, a conduit connecting the body and air chamber, a non-seating variably tensioned valve in the air chamber, and floating valve mechanism in the body to control the flow of air and gas therethrough, including a tubular valve stem having a valve at its lower end engageable with a seat for controlling flow of gas into the body, a main valve on the upper end of the stem engageable with a seat in the body, the valve at the lower end of the stem being constructed for admitting

gas to the bore of the tubular valve stem and auxiliary valve carried by the main valve for closing the bore at the upper end of the tubular valve stem, and the main valve having air 5 passage openings therein adapted to be closed by the auxiliary valve when the main valve is unseated.

4. In a natural gas carburetor, a body, an air inlet chamber, a conduit connecting the 10 body and air chamber, a non-seating variably tensioned valve in the air chamber, floating valve mechanism in the body to control the flow of air and gas therethrough, including a tubular valve stem, a main valve, a 15 valve on the stem, controlling flow of gas to the main valve and an auxiliary valve on the main valve, means forming unobstructed communication between the gas supply and bore of the tubular valve stem and said main 20 valve having air passage openings therein normally closed by the auxiliary valve, and radial ribs projecting inwardly of the body forming a guide for the main valve and providing a series of air and gas mixing chambers above the main valve.

5. In a natural gas carburetor, a body, an air inlet chamber, a conduit connecting the body and air chamber, a non-seating variably tensioned valve in the air chamber, and floating valve mechanism in the body to control the flow of air and gas therethrough, including a tubular valve stem having a valve at its lower end engageable with a seat for controlling flow of gas into the body, a main 25 valve on the upper end of the stem engage-

able with a seat in the body, the valve at the lower end of the stem being constructed for admitting gas to the bore of the tubular valve stem and auxiliary valve carried by the main valve for closing the bore at the upper end 70 of the tubular valve stem, and radial ribs projecting inwardly of the body forming a guide for the main valve and providing a series of air and gas mixing chambers above the main valve.

6. In a tubular gas carburetor, a body, an air inlet chamber, a conduit connecting the body and air chamber, a non-seating variably tensioned valve in the air chamber, and floating valve mechanism in the body to control the flow of air and gas therethrough, including a tubular valve stem having a valve at its lower end engageable with a seat for controlling flow of gas into the body, a main valve on the upper end of the stem engageable with a seat in the body, the valve at the lower end of the stem being constructed for admitting gas to the bore of the tubular valve stem and auxiliary valve carried by the main valve for closing the bore at the upper end 80 of the tubular valve stem, and the main valve having air passage openings therein adapted to be closed by the auxiliary valve when the main valve is unseated, and radial ribs projecting inwardly of the body forming a guide 85 for the main valve and providing a series of air and gas mixing chambers above the main valve.

In testimony whereof I affix my signature.
